Primary Examiner — Cynthia R Underwood(74) *Attorney, Agent, or Firm* — Dicke, Billig & Czaja, PLLC(57) **CLAIM**

The ornamental design for a strap end for a strap of a harness, as shown and described.

DESCRIPTION

Fig. 1 is a front perspective view of a strap end for a strap of a harness showing my new design;

FIG. 2 is a front elevational view thereof;

FIG. 3 is a rear elevational view thereof;

FIG. 4 is a top plan view thereof, the bottom plan view being a mirror image;

FIG. 5 is a left side elevational view thereof, the right side elevational view being a mirror image; and,

FIG. 6 is a top plan view thereof connected to a strap of a harness.

Those portions of the harness shown in broken lines depict an environment of use and form no part of the claim.

1 Claim, 6 Drawing Sheets(56)
